UNITED STATES PATENT OFFICE.

HORATIO B. RUGGLES, OF CHELSEA, MASSACHUSETTS, ASSIGNOR TO THE IDEAL CASTER MANUFACTURING COMPANY, OF SIOUX FALLS, SOUTH DAKOTA.

DESIGN FOR A CASTER-HOUSING.

SPECIFICATION forming part of Design No. 34,282, dated March 26, 1901.

Application filed February 2, 1901. Serial No. 45,792. Term of patent 3½ years.

To all whom it may concern:

Be it known that I, HORATIO B. RUGGLES, a citizen of the United States, residing at Chelsea, in the county of Suffolk and Commonwealth of Massachusetts, have invented and produced a new and original Design for a Caster-Housing, of which the following is a specification, reference being had to the accompanying drawings, forming part thereof.

Figure 1 is a top view of the caster-housing. Fig. 2 is a plan view of a caster-housing, showing my new design. Fig. 3 is a vertical sectional view.

As shown in the drawings, the leading or material feature of my design consists, first, of an upper body A of the caster-housing, having a shank c, a flat surface d on the top of the upper caster-ball housing, a curved surface e, a flat surface f, a threaded flange g for receiving and securing thereto the lower body

of the caster-housing or confining-ring B, which holds the caster-ball and ball-bearings in place, and a socket h for the ball-bearings and caster-ball, and, second, a lower body of the caster-housing B, in the shape of a hollow ring, called a "confining-ring," having a flat surface i, a curved surface j, and having the upper part of its inner side k threaded.

Having described my invention, what I claim as new, and desire to secure by Letters Patent, is—

The design for a caster-housing, as herein shown and described.

In testimony whereof I have signed my name to this specification in the presence of 35 two subscribing witnesses.

HORATIO B. RUGGLES.
